UNITED STATES PATENT OFFICE.

JAMES F. LOCKWOOD, OF PHILADELPHIA, PENNSYLVANIA.

DESIGN FOR A TOILET-POWDER BOX AND PERFUMERY-HOLDER.

SPECIFICATION forming part of Design No. 20,715, dated May 12, 1891.

Application filed April 2, 1891. Serial No. 387,448. Term of patent 3½ years.

To all whom it may concern:

Be it known that I, JAMES F. LOCKWOOD, a citizen of the United States, residing in the city and county of Philadelphia, State of Pennsylvania, have invented and produced a new and original Design for a Toilet-Powder Box and Perfumery-Holder, of which the following is a specification, reference being had to the accompanying drawings, forming part thereof.

The leading feature of my design for a toilet-powder box and perfumery-holder is a box having thereon a holder of the form of a pump.

In the drawings, Figure 1 is a perspective view, and Fig. 2 a central vertical section, wherein—

A designates a box for toilet-powder, and B designates a perfumery-holder of the form of a pump, composed of the stock C, the spout 20 D, handle E, and cap F.

Rising from the box are standards G, at the top whereof is a mirror H.

The face ornamentations of the box, pump, and standards form no part of the design, as 25 the same may be plain.

I claim—

A design for a toilet-powder box and perfumery-holder, substantially as shown and described.

JAMES F. LOCKWOOD.
